(57) **CLAIM**

The ornamental design for a mountable motion sensor, as shown and described.

DESCRIPTION

FIG. 1 is a perspective view of the mountable motion sensor.

FIG. 2 is a front elevation view thereof.

FIG. 3 is a rear elevation view thereof.

FIG. 4 is a left side elevation view thereof, the opposing right side being a mirror-image thereof; and,

FIG. 5 is a bottom plan view thereof.

(Continued)

The top plan view of the mountable motion sensor forms no part of the claimed design.
